ALBERT W. BINZ, OF PHILADELPHIA, PENNSYLVANIA, ASSIGNOR TO GEORGE N. SCHOFIELD AND EDWARD F. MASON, BOTH OF PHILADELPHIA, PENNSYLVANIA, COPARTNERS TRADING AS SCHOFIELD, MASON & CO.

LOOM FOR WEAVING DOUBLE PILE FABRICS.

1,137,832.

Specification of Letters Patent.

Patented May 4, 1915.

Application filed March 21, 1914. Serial No. 826,172.

To all whom it may concern:

Be it known that I, ALBERT W. BINZ, a citizen of the United States, residing at Philadelphia, Pennsylvania, have invented 5 certain new and useful Improvements in Looms for Weaving Double Pile Fabrics, of which the following is a full, clear, and exact description, reference being had to the accompanying drawings, forming a part of 10 this specification.

My invention relates to improvements in looms for weaving double pile fabrics comprising two spaced backing webs or cloths connected by pile threads which are woven 15 to extend across the space between the two cloths and to be afterward cut centrally between the two cloths to form independent pile fabrics.

Looms for weaving fabrics of this character employ spacing devices called pile-gages around which the double fabric is woven and which serve to properly space the two backing webs or cloths to preserve a uniform gage or length for the pile forming 25 portions of the pile threads extending between the cloths.

The object of my invention is to provide a pile-gage of novel, simple and efficient construction, whereof the portion which gages 30 and controls the distance between the two backing webs and the arm which holds the pile-gage in place, may be formed integral with each other in a single piece and of such form that a proper spacing of the two backing webs may be effected without injury to 35 the fabric.

A further object of my invention is to provide a novel pile-gage actuating heddle of such construction that it will not injure 40 the warp threads and of such construction that it may be readily applied to or removed from the horizontal rods or bars of a heddle frame.

To these ends my invented device consists of the elements and the combinations 45 of them hereinafter fully described and claimed.

In the accompanying drawings, illustrating 50 my invention. Figure 1, is a side view of my improved pile-gage and heddle therefor. Fig. 2, is an edge view of the pile-gage and heddle. Fig. 3, is a vertical section through a portion of a loom for weaving double pile fabrics, showing a portion of the

weaving mechanism and my improved pile-gage and heddle included therein.

Referring to the drawings, my improved pile-gage comprises a flat arm 2 having one end thereof tapered between upper and lower converging faces 3 and 4, respectively, 60 for purposes hereinafter explained.

My improved heddle for operating the pile-gage 2 comprises a pair of vertically disposed wires 5 between the central portions of which the end of the arm 2 having 65 the hole 6 therein is located. The wires 5 are twisted together, at 7, within the opening 6, at 8, directly below the arm 2, and, at 9, directly above the arm 2, thereby pivotally connecting the central portions of 70 the wires 5 to the arm 2 in a manner to permit the wires 5 to be moved vertically to raise and lower the connected end of the arm 2 while the free end of the arm 2 remains substantially in the same position. The adjacent upper ends and the adjacent lower ends of the wires 5 are twisted together and form eyes between the twisted portions 11 and 12 at each end of the heddle for the 75 reception of the spaced horizontal heddle-supporting bars or rods 13 of a heddle frame 14. It will be readily understood that by 80 untwisting the portions 12 at the two ends of the heddle, the heddle may be readily removed from the bars 13 of the heddle frame 14, without removing the bars or other heddles, to insert a new heddle, should 85 a heddle or its pile-gage be broken or otherwise rendered unfit for use.

When in use in a loom for weaving double 90 pile fabric, the pile gage 2 and its heddle are associated with the weaving mechanism as illustrated in Fig. 3, wherein 15 designates the upper portion of the lay, 16 the warp threads, 17 the raising and lowering 95 devices for the warp threads to form the sheds through which the shuttle or shuttles are projected during the weaving operation, 18 the upper web or backing cloth, 19 the lower web or backing cloth, 20 the pile-forming threads woven into and extending 100 between the upper and lower cloths 18 and 19, 21 the cutting knife for the pile threads, and 22 and 23 the rollers which support the cloths 18 and 19 around which they pass 105 as they are produced and the pile threads are severed. The backing webs or cloths 18 and 19 are formed at the points 24 and 25, re-

spectively, and pass therefrom in the direction of the arrows as rapidly as formed. The general construction and operation of the parts of the weaving mechanism for the manipulation of the threads in weaving the fabric are common and well known and no detailed description or illustration thereof is deemed necessary herein.

A number of the pile gages as illustrated in Fig. 3 are employed side by side in the loom and the heddle of each gage 2 is carried by the rods 13 of the frame 14, so that when the frame 14 is raised and lowered the entire set of pile gages 2 will be raised and lowered to positions above and below the shuttle path, as the different sheds are formed during the weaving operation. Any of the well known devices employed in looms to raise and lower heddle frames may be employed to raise and lower the frame 14.

The warp threads 16 extend between the heddles which carry the pile gages 2 and, during the weaving of the two backing webs or cloths 18 and 19, in the usual manner; the warp threads and heddles are raised and lowered with respect to each other; and, during this operation, my improved heddle permits relative movement between it and the warp threads without injury to the latter, as nothing but smooth rounded portions of the bent wires 5 are presented for contacting with the warp threads.

The free ends of the arms 2 constitute the pile gages, serving to maintain the two backing webs or cloths 18 and 19 the proper distance apart during the weaving of the entire double fabric; and, as rapidly as the fabric is formed and passes in the direction of the arrows, the fabric passes from the free ends of the pile gages 2. The free ends of the pile gages are supported by and between the two cloths 18 and 19. The point of connection between each arm 2 and its heddle is raised and lowered in a direct vertical line; and, therefore, as the arms 2 are raised and lowered, the free ends thereof are projected on into the space between the cloths 18 and 19 and withdrawn to the positions shown, as the arms move toward and from the horizontal central position between the uppermost and lowermost positions. When the arms 2 are in the lowermost position, as shown by full lines in Fig. 3, the upper face 3 is substantially parallel to the upper cloth 18, and when the arms 2 are in the uppermost position as shown by dotted lines in Fig. 3, the lower face 4 is substantially parallel to the lower cloth 19. This tapered end of the arm 2 formed between the converging faces 3 and 4 is an important feature of my invention as it enables me to maintain the proper vertical dimensions of the pile gage 2 at the fell of the cloth, at all times without having the free ends of the pile gages 2 engage and pro-

ject the upper cloth 18 above its normal horizontal plane, when the arms 2 are lowered, and without having the free ends of the pile gages 2 engage and project the lower cloth 19 below its normal horizontal plane, when the arms 2 are lowered, and I am thus enabled to prevent injury to the cloth and uneven weaving. Further, the tapered end of the pile gage enables it to work its way from between the cloths 18 and 19 as the arms 2 are raised and lowered, thus obviating the necessity of the employment of means to move the arms 2 longitudinally.

I claim:

1. In a machine for weaving double pile fabrics, the combination of weaving mechanism, an arm, and means operative to raise and lower one end of said arm, the other end of said arm being free and constituting a pile gage adapted to separate and to be supported by and between the upper and lower cloths being woven, and the free end of said arm having upper and lower converging faces lying wholly between the normal planes of said cloths in all positions of said arm.

2. In a machine for weaving double pile fabrics, the combination of weaving mechanism, an arm, and means operative to raise and lower one end of said arm, the other end of said arm being free and constituting a pile gage adapted to separate and to be supported by and between the upper and lower cloths being woven, the free end of said arm having upper and lower converging faces extending between said cloths, said upper face lying substantially parallel to said upper cloth when said arm is in the lowermost position and said lower face lying substantially parallel to said lower cloth when said arm is in the uppermost position.

3. A pile-gage comprising a body portion provided with means for connecting one end thereof to a raising and lowering mechanism and the other end thereof terminating in oppositely disposed upper and lower faces substantially straight and inclined toward each other, said inclined faces being out of alignment with the upper and lower faces of the main body of the pile-gage, and adapted thereby to lie wholly between the normal planes of the upper and lower cloths of the fabric in the alternating positions of said gage.

4. A pile-gage comprising a gage arm having an opening in one end, and a vertical heddle formed of two wire members having the central portions thereof twisted together within said opening, and having the end portions thereof formed into means adapted to engage the horizontal bars of a heddle frame.

5. A pile-gage comprising a gage arm, and a vertical heddle formed of two wire

members between which one end of said arm is located, said members being twisted together above and below said arm, and the end portions of said members being formed into means adapted to engage the horizontal bars of a heddle frame.

6. A pile-gage comprising a gage arm having an opening in one end thereof, and a vertical heddle formed of two wire members between which one end of said arm is located, said members being twisted together within said opening, and the end portions of said members being formed into means adapted to engage the horizontal bars of a heddle frame.

7. A pile-gage comprising a gage arm having an opening in one end, and a vertical heddle formed of two wire members having the central portions thereof twisted together within said opening, and having the end portions thereof provided with

spaced twisted portions forming eyes between the twisted portions for the reception of the horizontal bars of a heddle frame.

8. A pile-gage comprising a gage arm 25 having an opening in one end thereof, and a vertical heddle formed of two wire members between which one end of said arm is located, said members being twisted together within said opening, and the end 30 portions of said members being twisted together forming eyes between twisted portions thereof for the reception of the horizontal bars of a heddle frame.

In testimony whereof, I have hereunto 35 affixed my signature this 17th day of March A. D. 1914.

ALBERT W. BINZ.
